Specification for Design.

Patented Aug. 2, 1921.

Application filed February 2, 1921. Serial No. 442,001. Term of patent 7 years.

To all whom it may concern:

Be it known that I, LEE E. CLOUGH, a citizen of the United States of America, residing at Akron, in the county of Summit and State of Ohio, have invented a new, original, and ornamental Design for Solid-Rubber Tires, of which the following is a specification, reference being had to the accompanying drawings, forming a part thereof.

Figure 1 is a perspective view of the solid rubber tire embodying my new design, and Fig. 2 is a fragmentary view in section of said tire.

I claim:

The ornamental design for a solid rubber tire as shown. In testimony whereof I do now affix my signature.

LEE E. CLOUGH.
